COMBINED EYEGLASS TEMPLE AND HEARING AID CASING

John F. Rose, Minneapolis, and Harold W. Darr, Edina, Minn., assignors to Maico Electronics, Inc., Minneapolis, Minn., a corporation of Minnesota

Filed Dec. 24, 1959, Ser. No. 58,816

Term of patent 7 years

(Cl. D57—1)

FIG. 1

FIG. 2

FIG. 3

FIG. 4

FIG. 1 is a top plan view of a combined eyeglass temple and hearing aid casing showing our new design; FIG. 2 is an elevation view of one side thereof;

FIG. 3 is a bottom plan view thereof; and

FIG. 4 is an elevation view of the side opposite to that shown in FIG. 2.

We claim:

The ornamental design for a combined eyeglass temple and hearing aid casing, as shown,
